UNITED STATES PATENT OFFICE.

JOSEPH P. SMITHERS, OF BROOKLYN, NEW YORK.

TELEGRAPHIC REPEATER.

SPECIFICATION forming part of Letters Patent No. 268,561, dated December 5, 1882.
Application filed June 28, 1882. (No model.)

To all whom it may concern:

Be it known that I, JOSEPH P. SMITHERS, of Brooklyn, Kings county, New York, have invented certain new and useful Improvements 5 in Telegraphic Repeaters, of which the following is a specification.

My invention aims to provide a system of telegraphic repeaters which, while being efficient, shall involve a simpler and less expensive apparatus than those employed heretofore.

My invention is in the main original in its general character, but is in part an improvement on Toy's repeater.

15 Heretofore repeaters have been capable usually of repeating onto a single line only, whereas an important novel part of my invention enables the signals of one line to be repeated onto two or more lines.

20 The novel features constituting my invention will be elucidated in the course of the specification and distinctly formulated in the claims.

25 The annexed drawings represent my system diagrammatically in its different modifications.

Figure 1 represents the leading form of my invention adapted for repeating on a multiple number of lines, and Figs. 2 and 3 represent 30 a modified form adapted for repeating onto a single line.

I will first describe my two modifications of single repeaters shown in Figs. 2 and 3, in order that the more elaborate multiple repeater shown in Fig. 1 shall be more readily understood.

35 A novel advantage of my invention is that practically no addition is made to the ordinary telegraph apparatus; but the results sought 40 for are accomplished simply by the relative arrangement of the connections between the different parts of the usual telegraph apparatus.

Referring now to Figs. 2 and 3, it may be noted that the ordinary arrangement of the relay-magnets, main batteries, local magnets or sounders, and local batteries are employed.

45 *a a* indicate one telegraph-line coming in from the east to the station which Figs. 2 or 3 is presumed to represent, and this line may 50 hence be called the "eastern" line.

a' indicates the second or western line com-

ing into the same station, which two lines are operatively coupled by my improved repeater, so that the signals of one are repeated onto the other.

55 *c c'* indicate the relay-magnets of the respective lines; *d d'*, the main batteries; *e e'*, the ground-connections; *f f'*, the contacts worked by the relays; *g g'*, the local magnets or sounders, and *h h'* the local battery, which is in circuit, as usual, with the sounder-magnet and the relay-contacts, as illustrated.

60 It may now be noted that the local magnets or sounders *g g'* are provided with a double-armed armature-lever, *i i'*, similar to what is used in the Toy repeater, one arm being depressed by the attraction of the magnet and the other arm being depressed by the retracting-spring shown, each arm being provided with a set of contact-points, *k k'*. The contacts 70 *k*, which close by the attracting movement of the armature, may be called the "attracting-contacts," and the contacts *k'*, which close by the retracting movement, may be called the "retracting-contacts." Now, the arms of the 75 armature-lever, as may be observed, are of a springy or flexible nature, so that when the lever is tilted in either direction the open contacts will always be closed before or at the same time that the closed contacts are opened. 80

Now, referring to Fig. 2, it will be noted that the circuit of one of the telegraph-lines is completed through the attracting-contacts on the sounder of the other line. Thus the eastern line *a* passes through the attracting-contacts 85 *k''* of the sounder *g'* of the western line, and vice versa. This description will also apply in Fig. 3. By again referring to Fig. 2 it will be noted that the retracting-contacts *k'* on the eastern sounder *g* will, when closed, form a 90 short loop-circuit, *l l a a*, which will include the eastern relay-magnet *c* and a small or sectional battery, *m*, sufficient to overcome the resistance of the loop and energize the relay sufficiently to keep its contacts closed. In the 95 same manner the retracting-contacts *k'* on the western sounder *g'* are in a similar loop-circuit, *l' a'*, which involve the same corresponding parts on the western line.

100 The construction and arrangement of parts in Fig. 2 being now described, the operation is as follows: The apparatus is shown in its

quiescent condition, the circuit of both eastern and western lines being closed, the currents being hence represented as flowing in from the two distant stations, passing through the attracted contacts of the sounders, and flowing through the relays and the main batteries to the ground. The relays are hence magnetized and their contacts $f f'$ held closed, thus closing the circuit of the local battery upon the sounders $g g'$, and therefore holding the armatures of the sounders attracted, and thus keeping the attracting-contacts $k k'$ closed. If, now, the operator at the distant station on the eastern line a should break the circuit, the eastern relay c will of course become demagnetized, and its contacts f will open, thus breaking the circuit of the local battery h and sounder g , and thus demagnetizing the sounder-magnet and causing its armature to become retracted and to respond to the signal on the main line. As the armature i becomes retracted, however, it will first close the retracting or loop contacts k' , and immediately after open the attracting or "line" contacts k . The opening of the line-contacts k will of course break the circuit of the western line a' , and thus "repeat" the signal of the eastern line onto the western line; but the immediately-previous closing of the loop-contacts k' will close the loop-circuit $a' l'$ on the western relay c' , and thus prevent the eastern or sending line from becoming itself broken at the contacts k'' , which would of course occur if the western relay were allowed to become de-circuited. Hence, although a break on the sending-line is repeated on the receiving-line, yet the relay of the receiving-line is not de-circuited, but is always thrown into a short closed loop-circuit just previous to the break of the receiving-line, so that the sending-line is always kept intact at the repeating-station; otherwise it would of course be impossible for the distant operator to again close the sending-line if once broken at the repeating-station. Now, on the other hand, when the operator at the distant station again closes the circuit the parts will again assume their normal positions (shown in Fig. 2) and the "closing" signal on the eastern line will be repeated on the western line, as will be readily understood. It will also be readily understood that the action of the parts would be the same, but in reverse order, if the signals should be sent on the western line and repeated on the eastern line, so that the reverse direction of the operation need not be described.

In the Toy repeater the whole of the main battery was used to form a short circuit to the ground to hold the local or sounder magnet of the repeating-line closed, and hence the changing-of the powerful current of the main battery from the line into the short circuit to the ground necessitated the introduction of expensive rheostats or resistance coils into the short circuit, so as to render the resistance offered to the battery uniform when acting in the line or acting in the loop, in order to avoid injury to the instru-

ments, which would result from the frequent breaking of a strong current in a short circuit of low resistance. Instead of this, it will be noted that I effect a great improvement, in that I require no addition to the ordinary telegraph apparatus to produce my repeating system, and that I use a small sectional or supplementary battery, $m m'$, in a short loop-circuit, 75 before noted. This small battery may be provided by utilizing a section of the main battery, or by utilizing the ordinary local battery, or by employing a small independent battery. In Fig. 2, as before described, a section of the 80 main battery, m or m' , is included in the loop, while in Fig. 3 the loop-circuits are so disposed as to include the local batteries $h h'$ and the sounder-magnet directly, as shown. Fig. 3 is thus the same in construction and action 85 as Fig. 2, except that the local battery is arranged to energize the loop instead of a section of the main battery, and this loop acts directly on the sounder-magnet instead of on the relay. Either of these modifications may 90 be used, as occasion suggests, and hence Fig. 3 requires no further description than that given for Fig. 2, as may be readily seen by tracing the connections.

It may now be noted that in the simple or 95 single form of my invention, repeating simply from one line onto another or single line, as shown in Figs. 2 and 3, no additional instruments or batteries are required other than what is now employed, except the provision of 100 double contacts on the sounders. Hence I thus form a very simple and economical repeater, which is at the same time very certain and automatic in its action.

I will now turn to Fig. 1, which shows the 105 most elaborate form of my invention adapted for multiple repeating—that is, the signals of one line may be repeated onto any desired number of lines; and for this multiple apparatus some slight additions to the usual telegraph apparatus are necessary. In this case, referring to Fig. 1, I have shown three lines, A B C, coming into the repeating-station. I will first remark that the middle line, B, is here represented as switched out of the repeating 110 system, and hence only the outer lines, B and C, are coupled, so that the signals of B will be repeated on C, or vice versa. Any one or other of the lines might, however, be switched out or coupled up, as might be desired. The parts 115 of the middle line, B, are left unlettered in order to avoid confusion. In this multiple system it will be noted that each line is provided with two of the double-contact-making local instruments or sounders G G', similar to what 120 is shown in Figs. 2 and 3, whereas in Figs. 2 and 3 each line has but one of these instruments. Now, in Fig. 1 the main lines A or B pass through the attracting-contacts of the first of these contact-making instruments, G, 125 and its retracting-contacts control the loop-circuit $l C$ or $l A$ around the relays c , same as in Figs. 2 and 3; but, unlike the latter, the magnet of this first instrument is not in circuit 130

with the local battery and relay-contacts. Now, the second instrument, G' , has its magnet in the local-battery circuit, and hence this second instrument is the local sounder, which responds to the relay and to the signals of the sending-line. The second instrument, G' , I will therefore necessarily term the "local sounder," while the first instrument, G , I will term the "repeating-sounder," as it repeats the signals of the sending-line onto the receiving-line, as will hereinafter appear. These two instruments G and G' are, however, both arranged in relation to an additional local circuit, $n\ n\ n$, which I may call the "intermediate" or "repeating" circuit, which forms a characteristic feature of this part of my invention. This intermediate circuit is energized by the batteries $o\ o$, which are preferably arranged in sections along the circuit corresponding to the several lines $A\ B\ C$, as clearly illustrated, and it will also be noted that this intermediate circuit passes through the magnet of the repeating-sounders G and through the attracting-contacts of the local sounders G' .

It will be also noted that if the retracting-contacts of the local sounders G' are closed they will close a loop-circuit, $n\ o\ p$, in the intermediate circuit upon the magnets of the repeating-sounders G , this loop being supplied by one of the sectional batteries o , as shown.

It will be further seen that the intermediate circuit is provided with shunt branches n around each of the sectional batteries o , and around the two contact-instruments $G\ G'$ of any one of the lines $A\ B\ C$, with switches $r\ r$ arranged to complete the intermediate circuit through its direct path or through the shunts. Hence, if the switches are so set as to complete the intermediate circuit through any one of the shunts n' , the line corresponding to that shunt will be switched out of the repeating system, as is the case with the middle line, B , in Fig. 1, while if the switches are set to complete the circuit through the direct path—that is, through the contact-instruments $G\ G'$ of the respective lines—these lines will be coupled in the repeating system, as is the case with the lines $A\ C$, and hence the signals on one line will be repeated on the other.

We will now assume that the apparatus is in its quiescent condition, as shown in Fig. 1. In this case the intermediate circuit is of course closed, and the magnets of the repeating-sounders $G\ G'$ are hence energized and are holding the line-contacts $k\ A$ and $k\ C$ closed. The circuit of the lines $A\ C$ are of course also closed, and the currents thereof are hence flowing through the line-contacts $k\ k$, thence through the relays c and the main batteries to the ground. If, now, the line A is broken at a distant station, the relay thereof will break the circuit of its local sounder G' , and the armature thereof, in retracting, will first close the contacts k' , thus closing the sectional loop $n\ o\ p$ of the intermediate circuit, n , upon the repeating-sounder G of the sending-line A , and therefore prevents this instrument $G\ A$

from opening the sending-line, and immediately afterward the contacts k of the instrument G' will open, and thus break the intermediate circuit, n . As the intermediate circuit is thus broken the magnet of the repeating-sounder G on the line C will be demagnetized, and its armature, in retracting, will open the line-contacts k , and thus repeat the signal of the line A onto the line C . Just before the line-contacts k open, however, the loop-contacts k' close, thus keeping the relay $c\ C$ magnetized, and consequently keeping the local sounder circuit, and thus preventing the intermediate circuit from being broken at a second point—that is, at the contacts k of the local sounder G' of the line C —which would occur if the loop $C\ l$ were not at first closed. If, now, the distant operator closes the line A , the several parts referred to will again assume their closed position, (shown in Fig. 1,) and the closing-signal on line A will thus be repeated on line B . It will therefore be seen that the signals of one sending-line might thus be repeated on any number of receiving-lines that might be coupled with the repeating or intermediate circuit, n , thus accomplishing an important improvement, which, as may be seen, is effected with but comparatively simple additions to the ordinary telegraph apparatus.

It will be noted that the line B , which in Fig. 1 is switched out of the repeating system, may be operated individually for the transmission of messages direct to the distant station without interfering with the repeating action of the coupled lines $A\ C$. In Fig. 1, $s\ s\ s$ indicate the keys for individually operating any one line when not coupled for repeating.

It may be also noted, by referring to Fig. 1, that each of the repeating-sounders $G\ G'$ is provided with a small mechanical latch or lock, t , which may be so turned as to lock the armatures in their attracted positions, or so shifted as to release the armatures and permit them to play in obedience to the opening and closing of the intermediate circuit. Now, these catches should always be released on the instrument of the lines $A\ C$, which are coupled for repeating, but should be invariably closed on the instrument of the line B , which is switched out, as fully shown in Fig. 1, for it will be readily seen by referring to Fig. 1 that the magnet of the instrument G in the switched-out line B is cut out of the intermediate circuit, n , and hence if the armature of the instrument were not held down by the catch t its retraction would break the line B and close the loop-circuit with its relay.

In Fig. 2, $s\ s$ indicate the operating-keys for individually operating either of the two lines. When it is thus desired to operate either line separately the lines are uncoupled from the repeating system by the switches u , so as to break the loop-circuits $l\ a\ l'\ a'$ and close the main lines $a\ a'$ in branches a'' around the contacts $k\ k''$ of the sounders. The switches $u\ u$, as shown, are made in the form of a bisected tongue, so as to seat perfectly on the two

switch-points through which the circuit is completed.

In Fig. 3 the two lines are uncoupled for separate use by opening the switches u and closing the switches v , so as to break the loop-circuits and divert the main lines around the contacts of the sounders, as will be readily understood.

In the systems shown in Figs. 1 and 3 it is not necessary that the relay and local battery be used to operate the sounders, for the line-current may pass directly through the magnets of the sounders, if desired, thus operating them directly; but in most cases the relays and local circuits are necessary.

Any novel features which I may have shown but not claimed in this application I reserve for the subject of a future application, and I particularly reserve the broad claims on the intermediate circuit for a future application.

What I claim is—

1. In a repeating telegraph system, the combination, with two or more telegraph-lines, of a double-contact-making electro-magnet having one set of contacts closed by attraction and the other set closed by retraction, and so arranged that the open contacts close before or when the closed contacts open, with the circuit of one line completed through the attracting-contacts of said magnet, and with the coil of said magnet circuited so as to respond to the opening and closing of a second line, together with a short loop-circuit including the retracted contacts of said magnet, a small or supplemental battery, and the coil of a second contact-making magnet having attracted contacts which control the closing of the second line, whereby the breaking of the sending-line at a distant station will first close the said loop-circuit, and thus prevent the sending-line from being itself broken at the repeating-station, but will at the same time break the receiving-line, and thus repeat the message of the sending-line thereon, substantially as herein shown and described.

2. A repeating telegraph system consisting in the combination, with two individual telegraph-lines, each provided with relays and lo-

cal sounders, of double contacts worked by the sounders, and so arranged that one contact will close before or when the other opens, the circuit of one individual line being completed through the attracted contacts on the sounder of the other line, together with a short loop-circuit which includes a small or supplemental battery, the relay-magnet or its corresponding sounder-magnet, and the retracting-contacts of the sounder on the opposite line, substantially as herein set forth.

3. A multiple repeating telegraph system consisting in the combination, with two or more individual telegraph-lines, of an intermediate local or repeating circuit—such as n o —with which the several individual lines are related, and with a double-contact-making instrument, substantially such as G , having its magnet arranged in the said intermediate circuit and its attracted contacts in one of the individual lines, together with a second contact-making instrument, substantially such as G' , having its magnet circuited to respond to the breaking and closing of the individual line and its attracting-contacts arranged in the intermediate circuit, with a short loop-circuit—such as n o p —including the retracting-contacts of the said instrument and the magnet of the instrument G , substantially as herein shown and described.

4. In a multiple telegraph repeating system, the combination, with two or more individual lines, A B C , of the intermediate circuit, n n , and the contact-making instruments G G' , arranged substantially as shown relatively to the individual lines and to the intermediate circuit, with the intermediate line-batteries, o o , sectionally arranged, the sectional loop-circuits n o p , and the shunts n' in the intermediate circuit around the battery-sections, and the switches r to control the opening and closing of the shunts, substantially as and for the purpose herein shown and described.
